Oscar E. Heiberg

INVENTOR

UNITED STATES PATENT OFFICE.

OSCAR E. HEIBERG, OF BROOKLYN, NEW YORK.

PHONOGRAPH TRANSMITTING REPRODUCER.

Application filed March 23, 1920. Serial No. 368,169.

To all whom it may concern:

Be it known that I, OSCAR E. HEIBERG, a citizen of the United States, residing at 624 44th Street, in the borough of Brooklyn, 5 county of Kings, city and State of New York, have invented a certain new and useful Improvement in a Phonograph Transmitting Reproducer; and I do hereby declare the following to be a description of my 10 invention, such as will enable others skilled in the art to which it appertains to make and use same, reference being made to the accompanying drawing, and to the letters of reference thereon, which forms a part of 15 this invention.

This invention relates to phonograph reproducers and particularly to devices of this class adapted to transmit sound vibrations from a record to telephone receivers, radio 20 apparatus and the like located at a predetermined distance from the reproducer, and the object of this invention is to provide an improved device of the class specified with which circuit wires from a source of electrical 25 supply are connected and the vibrations of the reproducer being transmitted through a transmitter diaphragm, granular or ball carbon and through said circuit wires, a further object of the invention is to provide a 30 device of the class specified which is so constructed as to obtain a more noiseless, natural and clear reproduction of the subject of a record through suitable apparatus at a predetermined distance from the reproducer; and with these and other objects in view 35 the invention consists in a device of the class and for the purpose specified which is simple in construction and operation and efficient in use, and which is constructed and 40 operated as hereinafter described.

The invention is fully disclosed in the following specification, of which the accompanying drawing forms a part, in which the separate parts of my improvement are designated by suitable reference characters in 45 each of the views, and in which:—

Fig. 1 is a vertical section of a reproducer made according to my invention;

Fig. 2 a front view of the reproducer 50 shown in Fig. 1; and,

Fig. 3 a perspective detail view of a part of the construction shown in Fig. 2.

In the drawing I have shown at 1 the casing of a reproducer which is cup-shaped in 55 form or provided on one side face thereof with a recess in which a diaphragm 2 is

mounted and spaced between gaskets 3 held in place by an annular retaining ring 4.

A stylus or needle holder 5 having an aperture 6 is pivotally mounted in insulating blocks 7 mounted in connection with the casing 1. The blocks 7 will be composed of such insulating material as to insulate the mounting of the stylus holder 5 in connection with the casing 1, as hereinafter set out. 60 The holder 5 is adapted to detachably support a stylus or needle 8 as indicated in the drawing.

The upper end of the holder 5 is provided with a contact pin 9 which passes through the diaphragm 2 and cooperates with ball carbon 9^a. A contact wall 10 is mounted in the casing 1 inwardly of the diaphragm 2 and an insulated circuit wire is passed through casing 1 and is connected with the 70 pin 9 of the stylus holder 5. Another circuit wire 12 is passed into the casing 1, as clearly shown in Fig. 1, and indicated in Fig. 2.

The insulated blocks 7 are provided with contact points 14 composed of lead or a 75 composition of lead and other material, and these points pass into the aperture 6 of the holder 5 and form bearing or pivot members for said holder. Centrally of the back of the casing 1 is a projecting stud 15 by means 80 of which the reproducer may be mounted in connection with a suitable support.

The distinctive feature of my invention 85 consists in providing a reproducer of the class and for the purpose specified with a stylus or needle holder which is so mounted in connection with the reproducer casing as to be insulated therefrom, as well as the mounting of said holder on such pivots as to eliminate the harsh reproduction of the 90 sound waves of a record, whereby a selection 95 on a record may be reproduced through a suitable apparatus located at a predetermined distance from my improved reproducer, the vibrations being transmitted through 100 the electric circuit wires 11 and 12.

Having fully described my invention, what I claim as new and desire to secure by Letters Patent, is:—

A reproducer of the class described comprising a casing, a diaphragm mounted 105 therein, a contact in said casing inwardly of said diaphragm, a stylus holder pivotally mounted in blocks on said casing, said holder being provided with a contact pin which is secured centrally of said diaphragm and 110 electric wires passing into said casing and

one of which is secured to said contact pin, the pivotal connection of said stylus holder with said blocks being made by lead pivots for the purpose of eliminating the harsh reproduction of sound through said reproducer.

In testimony whereof I have signed my

name to this specification in the presence of two subscribing witnesses.

OSCAR E. HEIBERG.

Witnesses:

JOHN J. HARRISON,
IRVING McDONNELL.
